(57) **CLAIM**

The ornamental design for a container and overwrap assembly, as shown and described.

DESCRIPTION

FIG. 1 is a top perspective view of a container and overwrap assembly, showing our new design;

FIG. 2 is a bottom perspective view thereof;

FIG. 3 is a front elevational view thereof, the rear elevational view thereof being identical thereto;

FIG. 4 is a left elevational view thereof, the right elevational view being identical thereto;

FIG. 5 is a top plan view thereof; and,

FIG. 6 is a bottom plan view thereof.

The protrusions, recesses, and other portions of the container and overwrap assembly shown in broken lines are unclaimed environment, and form no part of the claimed design.
